UNITED STATES PATENT OFFICE.

WALTER E. BARNES, OF BINGHAMTON, NEW YORK, ASSIGNOR TO ENDICOTT JOHNSON CORPORATION, OF ENDICOTT, NEW YORK, A CORPORATION OF NEW YORK.

DESIGN FOR A TEXTILE FABRIC OR THE LIKE.

Application filed November 9, 1928. Serial No. 28,814. Term of patent 14 years.

To all whom it may concern:

Be it known that I, WALTER E. BARNES, a citizen of the United States, residing at Binghamton, in the county of Broome and State of New York, have invented a new, original, and ornamental Design for Textile Fabrics or the Like, as shown in the accompanying drawing, forming part of this specification.

The drawing shows a portion of a textile fabric or the like upon which the design, repeated in units bounded by the intersecting arrow lines, is applied.

The design may also be applied to analogous articles for use in the art.

I claim:

The ornamental design for a textile fabric or the like, substantially as shown and described.

WALTER E. BARNES.
